UNITED STATES PATENT OFFICE.

LEWIS M. ELLIS, OF CHICAGO, ILLINOIS, ASSIGNOR TO TUBAL BOILER CO., OF CHICAGO, ILLINOIS, A CORPORATION OF ILLINOIS.

HEATING SYSTEM.

Application filed April 25, 1921. Serial No. 464,381.

The present invention relates to heating systems, and is an improvement upon the heating system disclosed in my prior Patent No. 1,399,052, issued December 6, 1921.

5 In this patent I have disclosed a system of heating having particular application to ovens, kilns and other heating devices in which it is required to maintain relatively high temperatures, ranging in the neighborhood of between 350 degrees F. to 800 degrees F. These ovens or kilns have illustration in enameling ovens and the like. This heating system is characterized by the use of a superheated vapor or gas which is 10 mechanically circulated through the system at a sufficiently high speed to eliminate any tendency to condense in the oven coil or other heat radiating device. The vapor or gas is preferably, though not essentially 15 steam, and when employing this medium the system includes a superheater for adding heat to the steam, the oven, kiln or other heating device; and a pump, compressor, or the like which functions as an impelling device 20 for moving the steam through the circuit. A boiler or other source of steam or vapor is employed for making up the losses incurred in running and for supplying the initial body of fluid medium. The theory 25 of mechanically circulating the superheated steam at a relatively rapid rate through the oven coil is to prevent the temperature of the steam from dropping below the saturation point in the oven coil, and preferably 30 throughout the circuit, and to increase the heating efficiency of the coil by circulating the heat conducting medium therethrough at a relatively high speed.

35 One of the principal objects of the invention is to increase the efficiency of the circulating pump or blower by so disposing it in the system that it handles a relatively smaller or minimum volume of steam and at a point in the cycle where this steam is of 40 relatively low temperature. The reduced volume of steam permits of a smaller circulating device with a proportionate reduction in heat absorption by the circulating device, and the lower temperature of the steam 45 avoids overheating of the device and other mechanical difficulties.

50 A further object of the invention is to provide control means responsive to the temperature in the oven, or in the oven coil,

for controlling the rate of circulation 55 through the system, or for rendering ineffective the circulating device so as to interrupt circulation at a predetermined temperature.

A further object is to provide means for venting the circuit into a region of considerably lower pressure at predetermined times in the operation of the system, such as for the purpose of accelerating the rate of flow of the steam through the oven coil for the purpose of bringing the oven temperature up 60 to its desired value, or for more quickly initiating the operation of the system.

A further and prominent object of the invention is to provide means which will function as an elastic reservoir for releasing 65 heat and pressure from the circuit during periods when the oven is absorbing less than the normal or maximum amount of heat. During these periods the temperature of the superheated steam must be maintained at 70 substantially the same point as during the normal or high working conditions of the oven, but owing to the fact that a smaller quantity of heat is being absorbed in the oven, a large percentage of the original superheat given to the steam at the superheater 75 is returned to the boiler point of the circuit. Here this superheat is largely absorbed in the boiler, with the result that increased generation of steam follows. Where a very 80 large percentage of the original superheat is returned from the oven, this heat may be sufficient, when added to the external firing of the boiler, to generate an excessive quantity of steam in the boiler. The result is 85 that the steam pressure in the circuit tends to rise to an undesirable point, either from the stand-point of safety, or from the fact that it raises the saturation point of the vapor undesirably. In the present invention 90 I contemplate an efficient and economical method of compensating or absorbing these fluctuations in temperature and pressure by associating with the boiler or circuit either a steam engine, a heating apparatus, or any secondary heat absorbing means, and by regulating the external firing 95 of the boiler either manually or automatically to control the external heat input to the boiler in accordance with the pressure 100 in the system. According to this method, the boiler is externally fired to supply a substantially constant steam pressure of the de-

105

sired degree suitable for the oven circuit and for the secondary heat absorbing means. When the quantity of superheat imparted to the steam in the oven circuit is in excess of 5 the oven requirements the excess superheat heats the boiler internally and of itself or with the assistance of the external firing this internal heat tends to develop an excessive steam pressure. At this point, however, the 10 external firing of the boiler is cut down either by the attendant at the boiler or by automatic means. Owing to the forced circulation of the steam in the circuit and the high degree of superheat imparted there- 15 to, the heat returned to the boiler from the oven may be sufficient to generate excessive steam pressures even though the boiler is not being fired externally, so that it will be evident that some external heat absorbing 20 means is necessary to maintain the system balanced under all conceivable conditions. This secondary heat absorbing means is provided by the steam engine, steam heating apparatus, or other means, drawing steam 25 from the boiler point of the circuit. The relative capacities of the boiler and of the secondary heat absorbing means are preferably such as to insure that the secondary heat absorbing means will withdraw steam 30 from the boiler at a rate equal to or greater than the highest possible rate of steam generation caused by the returned superheat from the oven, so that the secondary heat absorbing means is always capable of utilizing 35 all of the returned superheat in order to avoid the generation of the excessive pressures in the system. From the foregoing it will be seen that the boiler, the secondary heat absorbing means, and the regulated fir- 40 ing of the boiler thus constitute an elastic thermal reservoir for withdrawing heat and pressure from the circuit during low working periods of the oven. Thus the system is made capable of meeting widely varying 45 demands, but at the same time, maximum heat economy is retained. The above feature of my invention may have the further aspect of efficiently utilizing the exhaust steam of lower temperature which is dis- 50 charged from the oven coil by secondary heat absorbing means having particular ap- 55 titude for this character of steam, as I shall hereinafter describe.

The foregoing objects will more clearly appear in the accompanying description of a preferred embodiment of my invention.

In the drawings illustrating this embodiment:

Figure 1 is a diagrammatic layout of one form of my improved system, and

Figure 2 is a similar view of another form of the system employing thermal controls for regulating the circulation through the system.

As fully described in the above men-

tioned patent, a boiler 4, which may be of any suitable type and capacity capable of generating the required pressure and volume of steam, supplies steam which is either saturated, or of a relatively low super-heat. 70 The steam is discharged from this boiler through a pipe 6 which extends to the intake of a circulating device 7. This circulating device may be of the reciprocating or rotary type, but is preferably a blower of 75 the centrifugal type, driven by a suitable motor 8. In forcing the steam through the circuit at the relatively high rate desired, this blower creates a boost in pressure at this point, so that the steam leaves the blower for admission into the superheater at a slightly higher pressure than that at which it is discharged from the boiler 4. From the blower 7 the steam flows through pipe 9 into a superheater 10, which may be 80 of any suitable character capable of imparting the required degree of superheat to the steam. The superheater illustrated is provided with a suitable burner, although it is to be understood that any controllable 85 source of heat may be employed. The burner is provided with a regulating valve 11 which controls the amount of fuel burned under the superheater. The rate of heat delivery to the superheater 10 is controlled 90 in accordance with the temperature of the heat transferring medium as it passes into the hot end of the oven or kiln 5. For this purpose, I have provided a temperature responsive element 12 for regulating the fuel control valve 11. The temperature responsive element 12, instead of being subjected merely to the temperature of the steam delivered, may be subjected to the temperature 95 of the kiln, or to the temperature of the exhaust steam discharged from the oven coil. From the temperature responsive element 12 the highly superheated steam flows through pipe 13 into the end of a heat radiating coil 14 in the oven 5. The coil 14 100 may be in the form of a single sinuated coil as illustrated, or it may consist of a plurality of coils connected in parallel between inlet and outlet headers. From the discharge end of the coil 14 the steam is 105 conducted back to the boiler 4 by way of pipe 15.

Any suitable secondary heat absorbing means may be connected to the boiler or to the circuit for cooperating with the boiler in providing an elastic thermal reservoir or excess heat absorbing means. At 16 I have shown an ordinary steam engine which may be run either constantly or intermittently, upon the return of excess heat to the boiler, this engine serving to drive any suitable power apparatus. The boiler is connected to this secondary heat absorbing means by way of pipe 17, a suitable valve 17' being interposed in the pipe. The regulation of the 110

furnace for the boiler 4 may be either manual or automatic, both being contemplated in the present method. Automatic regulation may be had by connecting a pressure responsive element 18 in the pipe line 17 or at any other point in the system preferably adjacent the boiler, and having this pressure responsive element control a fuel valve 19 and thereby regulate the external firing of the boiler.

In the operation of the system, the blower 7 circulates the steam through the oven coil 14 so fast that the drop in temperature of the steam by contact with the sides 15 of the tube 14 does not reduce the temperature of the steam to the point of saturation. Thus, the drop in temperature of the steam is controlled by the speed of movement of the steam and it is possible to hold the temperature of the coil very closely to a predetermined figure with only a small thermal drop, and consequently with an even distribution of heat throughout the coil. The oven temperatures which it is possible to obtain by this high speed circulation of superheated steam are far in excess of those ordinarily possible with saturated steam. For example, oven temperatures of from 500 degrees F. to 600 degrees F. can be maintained throughout the oven or kiln, with pressures in the neighborhood of 100 or 150 pounds. With saturated steam these temperatures would involve prohibitive pressures.

It will be noted that the blower 7 handles only the saturated steam passing from the boiler 4 to the superheater 10. This saturated steam has least volume and consequently the blower 7 can be of smaller size with proportionately less heat loss by conduction through the walls of the blower. Owing to the high superheat which must be imparted to the steam in the superheater 10 the expansion of the steam is relatively

large, and the handling of this expanded, high temperature steam on the outlet side of the superheater would require a large blower and involve unnecessary heat loss, even where the blower is disposed at the discharge end of the heating coil 14. Moreover, the lower temperatures of the saturated steam between the boiler 4 and the superheater 10 avoid large thermal losses, overheated bearings, and other mechanical disadvantages incident to the flow of a very high temperature gas through a blower.

The superheat returned from the oven to the boiler point of the circuit has the tendency to generate steam in the boiler, in quantities depending upon the amount of superheat and the balance or adjustment of the system. Were provision not made for taking care of this returned superheat the generation of steam therefrom might at times develop undesirable pressures in the

system. Any such increase in pressure would not influence the control element 12 as this element is only responsive to temperatures. According to the present method, where the firing of the boiler is manually controlled the attendant upon noting any such increase in pressure cuts down on the external firing. It is assumed that during this time the engine or other heat absorbing means is continuously withdrawing heat from the boiler. The excess heat may thus be drawn directly to the engine or indirectly in the form of steam vaporized in the boiler. The ultimate fact is that the engine requires a continuous supply of heat and when the oven circuit is operating normally a certain percentage of this heat is supplied by the furnace under the boiler, but when an excessive percentage of superheat is returned from the oven this heat is withdrawn from the oven circuit and is fed to the engine, the furnace heat under the boiler being reduced commensurately with the quantity of heat supplied from the oven circuit. Where the firing of the boiler is controlled automatically the generation of pressure in the system beyond a predetermined point operates automatically to reduce the rate of firing of the boiler. This shifts the thermal balance so that some, or more, of the excess heat from the oven is used in supplying the secondary heat absorbing means and less is supplied from the boiler furnace. It will be obvious that the system may have any desired thermal adjustment or balance. For example, a certain percentage of the heat returned from the oven may be supplied to the engine in the form of excess heat even when the oven is absorbing a relatively large amount of heat; or, the system may be so balanced that it is only when the oven is absorbing but little heat that the return heat therefrom is utilized to run the engine.

In the arrangement illustrated in Figure 2, saturated steam is supplied from a boiler 4 through pipe 6 to the blower 7, the blower in this instance being shunted by a by-pass 20 designed to control the circulation through the system. From the discharge outlet of the blower 7 the steam is conducted through pipe 9 to the superheater 10, and from the outlet of the superheater the superheated steam is conducted through pipe 13 to the oven coil 14, which may be arranged in either of the forms previously described. The temperature of the discharged steam is controlled by the usual temperature responsive element 12 which operates through the valve 11 to govern the rate of fuel supply to the burner of the superheater 10. For venting the coil 14 to atmosphere or to a region of lower pressure, the discharge end of the coil has an outlet opening 21 controlled by an automatic valve 22. To permit of manual venting of the

coil a secondary outlet 23 is provided, controlled by a manually operated valve 24. The two outlets 21 and 23 may discharge to atmosphere, or may vent into a heating system of lower pressure or any other region of sufficiently low pressure to insure a highly accelerated flow of steam through the coil 14. In the normal operation of the system, the steam is discharged from the coil 14 into the usual discharge pipe 15 which communicates with a steam main 25 extending from the boiler 4 to the engine 16. A check valve 26 is interposed in the pipe 15 to prevent the steam from backing up into the coil 14 during non-operating intervals of the oven.

The temperature of the oven 5 is maintained between predetermined limits by a suitable temperature control element 36. For controlling the predetermined maximum temperature of the oven this element 36 has connection 27 with a valve operating device 28 which controls a valve 29 interposed in the by-pass 20. For maintaining the temperature of the oven above a predetermined minimum, the element 36 has connection 30 with a valve operating device 31 which controls the automatic valve 22.

The same general theory of operation previously described is characteristic of this system. However, when the temperature in the oven 5 reaches a predetermined maximum, the temperature element 36 responds by opening the valve 29 through the instrumentality of the valve operating device 28 and connection 27. The result is that the forced circulation of the steam through the system is interrupted by the steam recirculating through the by-pass 20, and consequently the oven is given an opportunity to cool off, whereupon the valve 29 closes and the circulation through the oven coil is resumed as before. It will be noted that such steam as is circulated through the oven coil is maintained at a substantially constant temperature by the thermostatic control 12 and valve 11, the temperature responsive element 36 and valve 29 controlling the existence of a circulation through the oven coil or the volume of steam circulated therethrough. When the oven temperature recedes to a predetermined minimum, the temperature responsive element 36 operates to open the valve 22 through the instrumentality of the valve operating device 31, thereby causing a rapid discharge of steam from the discharge end of the oven coil with a consequent increase of steam flow through the oven coil in augmentation of that created by the blower 7. This results in a rapid rise of temperature in the oven, the valve 22 automatically closing when the desired temperature is restored. This increased rate of circulation through the oven coil for accentuated heating of the oven or for quickly

bringing the oven up to heat may be obtained at any time by the opening of the manually operated valve 24. The maximum temperature control 28-29 may be employed alone for controlling the temperature of the oven to the exclusion of the minimum temperature control 31-22, or vice versa. These control devices may be arranged to effect a graduated variation of the rate of circulation through the oven coil, or may be arranged to abruptly operate at their respective controlling temperatures for the rapid restoration of the desired oven temperature.

The relatively cooler steam from the discharge end of the oven coil may be circulated back into the boiler through the steam main 25; or it may be mixed with saturated steam drawn from the boiler 4 through the steam main 25 for the operation of the engine 16; or this discharge steam from the oven coil may be utilized for the running of the engine to the exclusion of the saturated steam from the boiler 4 by the closing of the valve 32 and opening the valve 17". That is to say, by closing the valve 32 and opening the valve 17" in the pipe line 25, the entire volume of steam discharged from the oven coils may be utilized for operating the engine 16. Of course, it would not be practical to do this except during low working periods of the heat radiating coils. The engine 16 in reality constitutes an independent secondary heat absorbing means associated with the heating system on the outlet side of the heat radiating coils for utilizing only heat in the vapor discharged from the coils in excess of that required for maintaining a predetermined pressure in the system. The engine 16 should, in order to attain the best results in the operation of the system, only be interposed in the return line of the system when a thermal outlet is needed, or in other words, when the coils are not functioning at their full capacity. The present invention, however, should not be limited to the specific type of secondary means employed, nor to the manner in which it is specifically associated with the system, but the invention should only be limited in so far as defined by the scope and spirit of the appended claims.

In this embodiment I have assumed the firing of the boiler as being manually controlled, although an automatic control such as previously described may be employed. A gage 34 indicates to the fireman or engineer the pressure in the system. By controlling the external firing of the boiler 4 the attendant can make the boiler and engine function as a thermal reservoir or heat absorbing means in precisely the same manner as before described. When the oven is returning a relatively large quantity of heat the boiler is fired at a proportionately lower rate. By closing the valve 32 the circulat-

ing action can be interrupted and the entire volume of steam from the oven can be diverted into the engine 16.

In the present form, the boiler 4 and superheater 10 are illustrated as being located in proximity so that the flue gases from the superheater 10 can be conducted through an exhaust flue 33 into the boiler 4 for a still further release of heat from the gases to the water in the boiler. The thermally responsive element 36 may be provided with any suitable gauge or indicating dial 36' for indicating externally the temperature existing in the oven 5.

15 I claim:

1. In a heating system, the combination in a vapor circuit, said circuit comprising a boiler, a superheater for superheating the vapor to a temperature above the temperature corresponding to the saturated vapor at the pressure prevailing in the system, a radiator in said circuit for receiving the superheated vapor, and impelling means interposed in said circuit between said boiler and said superheater for creating circulation with the relatively low temperature vapor.

2. In a heating system, a vapor circuit comprising a boiler, a superheater, a heat radiating coil, and a pump, said superheater heating the vapor to a temperature above the temperature corresponding to the saturated vapor at the pressure prevailing in the system, said heat radiating coil giving off heat from the vapor and reducing the temperature of the same to a point above the corresponding temperature of saturated vapor, said pump moving the vapor away from the radiating coil before the temperature of the vapor drops below the saturation point for the pressure prevailing in the circuit, said pump being interposed in said circuit between said boiler and said superheater, whereby said pump handles the low temperature steam of minimum volume passing between said boiler and said superheater.

3. In combination, vapor generating means, a vapor superheater, a heat radiator connected thereto, a vapor impelling means for driving the vapor through said superheater and said heat radiator, and means controlled by conditions at said heat radiator for automatically by-passing said vapor impelling means.

4. In a heating system, vapor generating means, a vapor superheater, a heat radiator connected thereto, a vapor pump for driving the vapor through said superheater and said heat radiator, a by-pass around said vapor pump, and thermally controlled means for automatically controlling said by-pass.

5. In a heating system, the combination of a vapor circuit, vapor generating means, said circuit including a heater for super-

heating the vapor, and a heat radiating device for receiving the superheated vapor, means for circulating the vapor through said circuit, and means for venting said circuit to a region of lower pressure for accelerating the flow of vapor through said heat radiating device.

6. In a heating system, a vapor generator, a vapor superheater and a heat radiator connected together in a circuit, a vapor pump for driving the vapor through said circuit, and means for venting said circuit to accelerate the flow of vapor through said heat radiator.

7. In a heating system comprising a vapor circuit, vapor generating means, a superheater in said circuit, a heat radiating coil in said circuit for receiving the superheated vapor, a vapor pump for circulating the vapor, and thermally controlled means for automatically venting said circuit to accelerate the flow of vapor through said heat radiating coil.

8. In a heating system, the combination of vapor generating means, a vapor circuit, a vapor superheater in said circuit, an enclosure having a heating coil therein included in said vapor circuit, a vapor pump for driving the vapor through said circuit, and thermally controlled means responsive to the temperature in said enclosure for automatically venting the circuit on the outlet side of said heating coil for accelerating the flow of vapor through said coil.

9. In a heating system, the combination of a vapor circuit, vapor generating means, a heater in said circuit for superheating the vapor to a temperature above the temperature corresponding to the saturated vapor at the pressure prevailing in the system, an enclosure comprising a coil in said circuit for giving off heat from the vapor and reducing the temperature of the vapor to a point above the corresponding temperature of saturated vapor at the same pressure, a blower in said circuit for driving the vapor through said heater and said coil, a by-pass shunting said blower, a vent in said circuit on the outlet side of said coil, and thermally controlled means responsive to the temperatures in said enclosure for automatically controlling said by-pass and said vent for controlling the circulation of vapor through said coil.

10. In a heating system, a vapor generator including an outlet, means for superheating the vapor in the system including an inlet, and impelling means for circulating the vapor in the system interposed intermediate the outlet of the vapor generator and the inlet of the superheating means.

11. In a heating system, a boiler for generating vapor, a superheater for superheating the vapor, and a pump for causing the vapor to be circulated interposed between the

boiler and the generator, said pump handling only the low temperature vapor of minimum volume passing between said boiler and said superheater.

5 12. In a heating system, a boiler for generating vapor, a superheater for superheating the vapor, radiating means disposed intermediate an outlet of the said superheater and an inlet of the boiler for receiving the 10 vapor, and impelling means disposed intermediate an outlet of the boiler and an inlet of the superheater for circulating the vapor through the system.

13. In a heating system, vapor generating 15 means, means for superheating the vapor, radiating means for receiving the superheated vapor, means for causing the vapor to be circulated through the system and thermally controlled means associated with 20 the radiating means for automatically venting the system when the temperature within the radiating means drops below a predetermined point to accelerate the flow of the superheated vapor through the radiating 25 means.

14. In a heating system, a source of steam, radiating means for receiving the steam and for taking heat therefrom, means for causing the steam to flow through the said radiating means, and thermally controlled means associated with the radiating means for automatically venting the system when the temperature within the radiating means drops below a predetermined point to accelerate the flow of the steam through the radiating means.

15. In a heating system, means for gen-

erating vapor, means for superheating the vapor, heat radiating means for receiving the superheated vapor, means for causing the vapor to be circulated through the system, and thermal means associated with the heat radiating means for venting the system when the temperature of the said heat radiating means falls below a predetermined amount and for by-passing the vapor around the circulating means to retard the flow of the vapor before it reaches the heat radiating means when the temperature of said heat radiating means exceeds a predetermined point.

16. In a heating system, a source of steam, heat radiating means for receiving the steam, means for causing the steam to flow through the said heat radiating means, and thermal means associated with the heat radiating means for venting the system when the temperature of the said heat radiating means falls below a predetermined amount and for by-passing the steam around the said second mentioned means to retard the flow of the vapor in the system when the temperature of the said heat radiating means exceeds a given amount.

17. In a heating system, a source of steam, a heat radiator, a first means for causing the steam to flow through the heat radiator, and a second means controlled by the conditions at the said heat radiator for automatically by-passing the steam around the first means to retard the flow of the steam in the system.

In witness whereof, I hereunto subscribe my name this 13th day of April, 1921.

LEWIS M. ELLIS.
